CLAIM

The ornamental design for a lawn arm assembly for attaching an edger to a mower, as shown and described.

DESCRIPTION

FIG. 1 is a top plan view of a lawn arm assembly for attaching an edger to a mower showing my new design;

FIG. 2 is a front elevation view thereof;

FIG. 3 is a right side elevation view thereof;

FIG. 4 is a bottom plan view thereof;

FIG. 5 is a rear elevation view thereof;

FIG. 6 is a left side elevation view thereof; and,

FIG. 7 is a top left perspective view thereof shown in use condition.

The broken line showing of an edger and mower in FIG. 7 is included for the purpose of illustrating environmental structure and forms no part of the claimed design.
